UNITED STATES PATENT OFFICE.

ERNEST SIEGEL, OF NEW YORK, N. Y.

LUBRICATING DEVICE.

Application filed February 4, 1926. Serial No. 85,911.

The relatively movable parts of some ignition timers for internal combustion engines require lubrication such, for example, as the ignition timer furnished as standard equipment upon the well known Ford automobile, and the present invention relates more particularly to improved means for effecting the lubrication of this timer.

In the ignition timer referred to, the outer end of the outwardly closed casing shell is provided in its upper side with an oil hole, but it has been found that the oil supplied to the interior of the casing through this oil hole quickly runs out of the casing at its other end, which is open and merely fits up against the engine frame to provide for rotative adjustment of the casing, and even if the oil were retained in this inner open ended part of the casing, it would there be at a point of no value for lubricating purposes. When the oil is insufficient, as is the case most of the time, the wear on the relatively movable contact making and breaking parts is excessive and uneven so that these parts soon wear to such an extent, particularly the circular track for the rotating contact maker, that good contacts for establishing the ignition circuit are not made, thereby sometimes failing to ignite the fuel charge in the engine. The expedient has been tried of packing the outer closed end portion of the timer casing with a relatively hard grease, which would not run out of the casing, but it has been found that this grease does not supply adequate lubrication. These above noted troubles, due to ineffective lubrication, with the ignition timer furnished as standard equipment upon the well known Ford automobile, have been long recognized, but so far as I am aware have not been remedied in this timer although many attempts have been made to overcome these difficulties by designing or inventing entire timing devices intended to take the place as a whole of the timer installed as standard equipment on the Ford cars.

An object of this invention is to provide means for feeding continuously to the relatively moving parts of the ignition timer just the required amount of lubricant. Another object of the invention is to provide a lubricating device, which may be readily installed in the timer casing so as to cooperate with the features of construction of the timer as originally manufactured. Another object of the invention is to provide a

lubricating device which may be quickly and conveniently applied to the timer or removed therefrom. Another object of the invention is to produce an inexpensive lubricating device of the kind referred to which may be independently manufactured and sold as a separate unit to be applied to the timer by any one to form a feature of improvement therein. Other objects and advantages of the invention will hereinafter appear.

According to my invention lubricating oil is fed by means of a suitable wick to the parts of the ignition timer requiring lubrication. More particularly in carrying out the invention, and as shown in the illustrated embodiment thereof, a unitary insertable and removable lubricating device is provided comprising a removable partition member to extend across the closed outer end portion of the usual rotatively adjustable timer casing, this partition member forming an oil receiving chamber in the outer end of the timer casing, and having a central cap portion to receive the outer end of the timer shaft. A circular or annular wick is provided outwardly from the partition member within the oil chamber, the partition member being clamped by releasable means against the usual shoulder formed in the outer tapering closed end of the timer casing with this circular wick forming an interposed insulating and sealing gasket to retain oil in the oil chamber. This wick also acts as a feeder wick for a second wick which is an oil-supplying wick extending from within the oil chamber through aligned openings in the circular wick and in the margin of the partition member in the lower part of the timer casing, the rotating contact member of the timer having wiping engagement with the inner end portion of this second or oil-supplying wick to receive oil therefrom, such wiping engagement taking place at each rotation of the timer shaft.

The invention further includes features of construction and combinations of parts as will appear from the following description.

One embodiment of the invention is shown in the accompanying drawings and the invention is pointed out in the appended claims. The illustrated embodiment of the invention will now be described with reference to the drawings, in which:

Fig. 1 is a central vertical section on the line 1—1 of Fig. 2 showing a lubricating device according to the present invention as

embodied in an ignition timer of the well known Ford construction.

Fig. 2 is a rear elevation of the complete ignition timer embodying my invention as viewed from the left in Fig. 1;

Fig. 3 is a rear face view in elevation of the lubricating device, per se, in the position in which it appears in Fig. 2 but shown independently of or separately from the rest of the timer as a whole;

Fig. 4 is a partial horizontal section on the line 4—4 of Fig. 2 showing more particularly the releasable fastening means for removably retaining the lubricating device as a whole in place in the timer casing;

Fig. 5 is an edge or side elevation of the complete unitary lubricating device, as viewed from the right in Fig. 3, and corresponding to the position in which it is shown in section in Fig. 1.

For a clear understanding of the lubricating device of the present invention, it will be necessary first to describe briefly the timer for ignition systems as originally manufactured without having this invention embodied therein.

From the side of the engine frame (not shown) of the Ford automobile, there projects a rotating timer shaft 1, the projecting end of which carries a rotatable contact member or distributing member for successively making and breaking the connections of the ignition circuit with the four spark plugs of the engine. This contact member includes an inner arm 2 which by means of its hub is removably mounted upon the projecting end of the timer shaft 1 to rotate therewith, being keyed thereto by means of a pin 3, and being retained upon the shaft by means of a nut 4 so that merely by removing the nut 4 the arm 2 together with the parts carried thereby may be removed from the timer shaft 1. The outer end of the arm 2 has pivoted thereto at 5 a trailing wiper arm 6 which at its free end carries a contact roller 7 on a journal pin 7^a and which is pressed outwardly to its contact-making position by means of a small coiled retractile spring 7^b, which is anchored to a lug on the hub of the inner arm 2 and connected to a tail on the outer arm 6. The timer shaft 1, the arms 2 and 6, and the contact roller 7, including the pivot pin of the latter, of course all are of metal so as to form a conductive path in the ignition circuit.

An inwardly open and outwardly closed rotatively adjustable contact-carrying metallic casing shell 8 removably fits over the outer projecting end of the timer shaft 1 and the above described contact member mounted thereon. The casing 8 is substantially of cup shape having a cylindrical inner or body portion open at its inner end and at its closed end tapers along curved

lines, thereby forming a shoulder within the casing adjacent to its cylindrical body portion, as clearly shown in Fig. 1. The inner open end of the casing 8 fits against the outer face of the adjacent side wall of the engine casting within a slight annular ridge or flange provided on the engine frame, and is removably held in place by means of a yoke arm (not shown) which carries a screw to engage in the indentation shown centrally in the outwardly tapering closed end of the casing, this yoke arm being mounted on the engine casting. A lever arm 9 shown as secured to the upper side of the casing 8 towards the front thereof provides for the connection of the usual controlling rod, which in turn is connected to the usual spark lever for thereby manually rotatively adjusting the casing 8 together with the contacts and other parts carried thereby. An oil hole is shown as provided through the upper side of the forwardly tapering part of the casing 8 through an oil tube or cup 10 which at its outer end is provided with a hinged cover as shown in Fig. 1.

Within its larger cylindrical inner portion and substantially midway of the length thereof, the casing 8 carries an insulating ring or annulus 11, which in turn carries four equidistantly spaced metallic contacts 12 which are countersunk into the inner face of the insulating ring 11 so as to have their inner arcuate surfaces flush with the inner surface of the ring 11. Each of the contacts 12 is provided with a conductive stud 13 which passes outwardly through the insulating ring 11 and through an insulating sleeve 14 in the metallic casing 8 and at its outer screw-threaded end is provided with one or more nuts 15 so that the studs 13 thus form binding posts from which the circuit wires lead to the spark plugs, respectively. These studs 13 also serve to retain the contact-carrying insulating ring 11 in place within the casing 8, it being noted that this ring 11 projects radially inward from the inner cylindrical surface of the casing 8 so as thereby to provide a shoulder-forming ridge or ledge therein. The contact roller 7 runs or travels upon the smooth circular inner surface provided by the insulating annulus 11 and the conducting contacts 12 for thereby making and breaking the ignition circuit through these contacts.

The improvements effected in this timer for assuring effective lubrication according to my invention will now be described.

Reference will first be had more particularly to Figs. 3 and 5 of the drawings, which show the unitary lubricating device of my invention as segregated from the other parts of the timer in which such lubricating device is shown as embodied in Figs. 1, 2 and 4. A metallic partition member 16 for the casing 8 comprises, as shown in

the drawings; a flat outer annular flange portion and a central cap portion for receiving and enclosing the outer projecting end of the timer shaft 1 and its nut 4. This partition member 16 may be made in one piece, as shown, of any suitable metal and it may be an inexpensive die-casting or, if desired, it may be readily stamped from sheet metal. An initially flat annular wick 17 fits snugly over the slightly outwardly tapering cap portion of the partition member 16 in contact with the front face of the flat flange portion of this member, beyond the outer circular edge or periphery of which the outer margin of this wick projects to a considerable extent, shown in the drawings, in the flat condition of this wick as shown in Figs. 3 and 5, as substantially equal to the width of the flange portion of the partition member 16. A second wick 18 in the form of a strip and which may be a piece of ordinary lamp wick, is threaded through an arcuate slot of suitable length, shown in the drawing as having a length of a little less than 80 degrees, provided through the flat flange portion of the partition member 16 adjacent to its lower edge, this wick being sufficiently gripped in the slot to be held in adjusted position therein, and this wick also passing through a slit made in the annular wick 17 to register with the slot in the member 16, as shown in Figs. 1 and 5 of the drawings. This second wick 18 projects to a considerable distance inwardly or rearwardly from the partition member 16 and is shown as projecting to a greater extent outwardly or forwardly from the annular wick 17. Both of the wicks 17 and 18 may conveniently and effectively consist of ordinary wick fabric. Means are provided for removably holding the partition member 16 together with the wicks 17 and 18 carried thereby in place within the timer casing 8 and for this purpose such means may conveniently engage with the internal forward shoulder or ledge formed by the insulating ring 11 within the casing 8. Such holding or retaining means are shown in the illustrated construction as carried by the partition-forming member 16. The means shown comprise two diametrically disposed leaf springs 19 each of which at one of its ends is pivoted by means of a rivet 20 to the flat flange portion of the partition member 16 to swing laterally on the inner or rear face thereof, and the free ends of these springs are bent away from the partition member 16 as shown in Figs. 3 and 4. These leaf springs 19 form catches or fasteners which may be swung to retract them to the disengaged position shown at the right in Fig. 3, or they may be swung to project them to the engaging or holding position shown in Fig. 4 and at the left in Fig. 3. The construction of the lubricating device per se of the invention has now been described and reference will now be had more particularly to Figs. 1, 2 and 3 of the drawings for describing the new and improved construction of the ignition timer produced by embodying the above described lubricating device therein as a feature of improvement thereof.

The partition-forming member 16 is made of just sufficiently smaller diameter than the central opening formed in the casing 8 within the insulating ring 11 when the casing carrying this ring is removed or detached from the engine so that the partition member 16 together with the two wicks carried thereby, the annular wick 17 of which automatically folds itself at its projecting margin around or over the edge of the partition member 16, may be readily pushed through the insulating ring 11 with the cap portion of the partition member 16 and the annular wick 17 towards the closed outer end of the casing 8, the spring fasteners or catches 19 then being in the retracted positions shown for one of these catches or latches at the right in Fig. 3. It is to be noted that these catches are positioned on the partition member 16 so that they may swing thereon without the inwardly projecting end of the second wick 18 being in their path, as appears in Figs. 2 and 3, and in inserting the lubricating device into the casing 8 it is positioned so that the wick 18 will be adjacent to the lower side of the casing as is shown in Figs. 1 and 2, and as is indicated in Figs. 3 and 5. When the lubricating device is thus pushed into the casing 8 as far as the internal shoulder formed by the tapered forward part of the casing will let it go, the outer margin of the annular wick 17 will project beyond the adjacent track surface of the insulating ring 11, and this projecting marginal portion of the wick 17 is to be pushed back into the casing at the front of the insulating ring 11 within the outer cylindrical portion of the casing 8, and this wick may be first thus pushed back to provide a clearance space for the spring catches 19. While the lubricating device is manually held in position in the casing these catches 19 are swung to their projecting position so as to engage their rearwardly turned free ends, the corners of which may be slightly rounded, at the front of the insulating ring 11 at a point between two of the contacts 12 carried thereby, as shown in Figs. 2 and 4, thereby securely to clamp the lubricating device in place within the casing 8 with the outer marginal portion of the annular wick 17 gripped between the shoulder formed by the tapering front wall of the casing and the outer edge portion of the partition-forming member 16. Using any

suitable tool, such as an ordinary screw-driver, the outer margin of the annular wick 17 should be pushed radially outward all around into the annular internal pocket 5 formed between the insulating ring 11 and the adjacent portions of the wall of the casing shell 8, so as to lie snugly against the casing with its edge turned over inwardly of the casing in J shape in contact 10 with the forward surface of the insulating ring 11 and terminating short of or radially outward from the inner surface or circular track provided by the insulating ring 11 and contacts 12 and upon which the contact 15 roller 7 runs, as shown in Figs. 1, 2 and 4.

The clamping of the partition member 16 in place by means of the catches 19 as above described clamps and grips the annular wick 17 with sufficient force to provide an 20 adequate seal so that thereby the partition member 16 forms an oil-receiving chamber in the outwardly tapered closed forward end portion of the casing shell 8, as most clearly 25 appears in Fig. 1. The outwardly rounded end of the cap portion of the partition member 16 presses against the outwardly or forwardly projecting portion of the lower wick 18 to hold it against the adjacent 30 downwardly inclined wall of the casing, as shown in Fig. 1. The other end portion of the lower wick 18, which projects rearwardly beyond the partition member 16, is turned over downwardly as shown in Figs. 1 and 2 and is substantially flush or in line 35 with the forward face of the insulating annulus 11 in position for the end of the contact roller 7 to have wiping oil-receiving engagement therewith while it is passing through the corresponding arc of its planetary travel. Should this portion of the wick 40 become worn, it may be trimmed if necessary and suitably adjusted to correct position through the slot in the partition member 16. In view of the fact that the 45 metallic catches 19 engage the insulating ring 11, the metallic parts of the lubricating device cannot short circuit the ignition circuit, further insulation being provided by the annular wick 17 between the metallic 50 partition member 16 and casing 8. The lubricating device may be readily removed from the timer casing 8 merely by releasing the clamping catches 19. Oil introduced, through the oil tube 10, into the 55 above described oil chamber formed in the outer end of the casing 8 by the partition member 16 will be absorbed by the wicks 17 and 18 and will be transferred by capillarity to the portions of these wicks beyond 60 or at the rear side of the partition member 16, where oil will be supplied by the lower wick 18 to the contact roller 7 in its wiping contact with this wick, and this oil will be transferred by the contact roller 7 65 to the surface of the track upon which it

runs to provide a thin film of oil thereon at all times, and it has been found that just the right condition of lubrication is provided in this way for the most effective operation of the timer and to prevent undue wear. At the same time, it will be noted, that the journal bearing 7^a of the contact roller 7 will also be lubricated. Some oil will also creep by capillarity from both of the wicks over the track of the 70 roller 7 in the ring 11. Also the contact of the margin or edge portion of the annular wick 17 with the end surface of the insulating ring 11 will result in some oil being absorbed by this ring so that in a 75 short time it becomes sufficiently permeated with oil to substantially increase its wearing qualities. It is to be noted that the annular wick 17 acts as an auxiliary wick to feed oil to the lower wick 18 which is an 80 oil-supplying wick for effecting the lubrication of the relatively movable parts of the timer. Whatever quantity of oil that may be desired may be introduced into the oil 85 chamber and it will be used gradually as required. Should there be no surplus oil in the chamber, the oil-soaked wicks will continue to furnish effective lubrication for some time, until the oil supply can be replenished. 90

It has been found that the lubricating device illustrated in the drawings as an embodiment of the invention effectively meets the requirements to fulfil the objects of the invention, however, it is to be understood as obvious that various modifications may be made in the construction shown in the drawings and above particularly described within the principle and scope of the invention as defined in the appended claims. 95

I claim:

1. In a timer for ignition systems comprising a rotatively adjustable lubricant-receiving casing provided with circularly arranged contacts exposed at its inner side and enclosing a rotating contact maker having wiping engagement with the contacts in the casing, the combination with said casing and contact maker of a lubricating device comprising a lubricant-supplying wick disposed within and near the lower side of the casing in position for the contact maker to have wiping engagement with it, an auxiliary wick disposed transversely across the casing and in close contact with the said lubricant-supplying wick to feed the lubricant thereto, and means for holding the wicks in position in the casing. 110

2. In a timer for ignition systems comprising a rotatively adjustable lubricant-receiving casing shell closed at its outer end and having at its inside an annular ledge carrying inwardly exposed contacts and enclosing a rotatable contact having wiping engagement with the contacts carried by the 115 120 125 130 135

- annular ledge, the combination with said casing shell and rotatable contact of a lubricating device comprising a lubricant-supplying wick positioned in the outer closed end of the casing shell near its lower side for the rotatable contact to have wiping engagement therewith, an auxiliary wick disposed transversely across the casing shell and in close contact with the said lubricant-supplying wick to feed the lubricant thereto, and means for holding the wicks in position having releasable engagement with said annular ledge thereby to permit the lubricating device to be inserted into and removed from the casing shell through the annular ledge.
3. An insertable and removable lubricating device for a timer for ignition systems comprising a partition member for the timer casing to form an oil-receiving chamber therein, a wick for conveying oil from the oil chamber past the partition member to the timer parts, and means for removably holding the partition member and wick in position in the timer casing.
4. A lubricating device for a timer for ignition systems comprising an insertable and removable partition member for the timer casing for forming an oil-receiving chamber therein, a wick carried by the partition member for conveying oil from the oil chamber beyond the partition member to the timer parts, and means for removably retaining the partition member and thereby the wick in place in the timer casing.
5. A lubricating device for a timer for ignition systems comprising an insertable and removable partition member for forming an oil chamber in the timer casing, the partition member having a slotted opening adjacent one edge thereof, a wick passing through said opening for conveying oil from the oil chamber for lubricating the timer, and releasable means for removably holding the partition member together with the wick in place in the timer casing.
6. A lubricating device for a timer for ignition systems comprising an insertable and removable partition member for the timer casing, a wick to form a gasket around the margin of the partition member, a wick for conveying oil from one side of the partition member to the other, and releasable means for removably holding the partition member and the wicks in place in the timer casing.
7. An insertable and removable lubricating device for a timer for ignition systems comprising a partition member for forming an oil-receiving chamber in the timer casing, a gasket-forming wick carried by the partition member to be clamped thereby against the wall of the timer casing, an oil-supplying wick carried by the partition member for conveying oil from the oil chamber to a point beyond the partition member, and releasable means for clamping the partition member against the wall of the timer casing thereby to hold the said device in place in the timer casing.
8. An insertable and removable lubricating device for a timer for ignition systems comprising a circular partition member for the timer casing provided with a central cap portion to receive the projecting end of the timer shaft, an annular wick fitting over said cap and of larger external diameter than said member, said member and wick having aligned openings in their marginal portions, an oil-supplying wick passing through and held in said aligned openings, and releasable means for removably holding the said device in place within the timer casing.
9. An insertable and removable lubricating device for a timer for ignition systems comprising a circular partition member for the timer casing provided with a central cap portion to receive the projecting end of the timer shaft, an annular wick fitting over said cap and of larger external diameter than said member, said member and wick having aligned openings in their marginal portions, an oil-supplying wick passing through and held in said aligned openings, and fastening means movably mounted on said member for removably holding the said device in place in the timer casing.
10. An insertable and removable lubricating device for a timer for ignition systems comprising a circular partition member for the timer casing provided with a central cap portion to receive the projecting end of the timer shaft, an annular wick fitting over said cap and of larger external diameter than said member, said member and wick having aligned openings in their marginal portions, an oil-supplying wick passing through and held in said aligned openings, and fastening means movably mounted on said member for removably holding the said device in place in the timer casing, said fastening means comprising a plurality of leaf spring catches pivoted on the margin of the partition member to swing laterally on its face opposite to the annular wick and having free ends turned away from the adjacent face of said member and to be swung beyond the peripheral edge of said member for resiliently clamping the said device in the timer casing and to be swung within the outer edge of said member to provide for removing the said device from and inserting into the timer casing.

In witness whereof, I hereunto subscribe my signature.

ERNEST SIEGEL.
